UNITED STATES PATENT OFFICE

168,805

TAIL LIGHT FIXTURE FOR AUTOMOBILES

Wayne R. Porter, Kansas City, Mo.

Application April 17, 1952, Serial No. 19,361

Term of patent 3½ years

(Cl. D48—32)

To all whom it may concern:

Be it known that I, Wayne R. Porter, a citizen of the United States, residing at Kansas City, in the county of Johnson and State of Missouri, have invented a new, original, and ornamental Design for a Tail Light Fixture for Automobiles, of which the following is a specification, reference being had to the accompanying drawing, forming a part thereof.

Fig. 1 is a face view of a tail light fixture for automobiles showing my new design; and

Fig. 2 is an edge view thereof, partially broken away.

The drawing is lined to show contrasting colors.

I claim:

The ornamental design for a tail light fixture for automobiles, as shown and described.

WAYNE R. PORTER.
